UNITED STATES PATENT OFFICE.

GEORGE LEWIS, OF CHICAGO, ILLINOIS.

LADY'S SKIRT.

SPECIFICATION forming part of Letters Patent No. 698,205, dated April 22, 1902.

Application filed February 3, 1902. Serial No. 92,384. (No model.)

To all whom it may concern:

Be it known that I, GEORGE LEWIS, a citizen of the United States, residing at Chicago, in the county of Cook and State of Illinois, have 5 invented a certain new and useful Improvement in Ladies' Skirts, of which the following is a specification.

My invention relates to skirts for ladies and misses, having reference more particularly to 10 underskirts, although my invention is equally capable of application to overskirts where desired.

My invention is designed for use more particularly in connection with skirts which are 15 capable of being washed when soiled, and in connection with such articles has for its primary object to provide a device whereby the lower and outer portion of the skirt, which is more particularly subject to being soiled, may 20 be readily removed and laundered without the necessity of laundering the entire gown.

To this end my invention resides in the combination, with the body of a skirt, of a removable ruffle or flounce for the lower portion 25 thereof, which is adapted to be united to the body of the skirt by a readily-separable joint or connection involving novel features of construction and operation, substantially as hereinafter described, and more particularly 30 pointed out in the claims.

My invention is illustrated in the accompanying drawings, in which—

Figure 1 is a side elevation of a lady's skirt having my invention applied thereto, and 35 Figs. 2 and 3 are enlarged details illustrating my improved device for detachably uniting an outer ruffle or flounce to the body of the skirt.

In the drawings, A represents the body of 40 the skirt, which is in the usual form. In carrying out my invention I preferably provide a tuck B entirely around the lower portion of the skirt at a suitable height from the bottom thereof to accommodate the application there- 45 under of the upper margin of a ruffle or flounce, (indicated at C.) To the body of the skirt, underneath the tuck B, is applied a circular strip of open-work insertion or beading, (designated by D,) this beading being con- 50 veniently stitched to the base, as indicated at d. It will be observed that the central portion of this beading is constituted by a series

of loops, (indicated at d'), which are of sufficient size to permit the ready threading or lac- 55 ing therethrough of an interlocking cord, as hereinafter described. To the upper edge of the flounce or ruffle C is stitched along its lower edge, as shown at c, a strip of open-work insertion or beading E, which may be of the same form and material as the strip D. 60

In applying the flounce C to the skirt, the strips of beading D and E having been stitched to the skirt and flounce, respectively, in the manner described, the flounce is laid in place with its upper marginal strip of beading E di- 65 rectly overlying the companion strip D on the skirt. A coarse needle threaded with a cord F is then run through the looped portions of the two strips, the cord being interwoven loosely between said loops and locking them 70 together. After the cord has thus been thread- ed through the overlapping strips for the entire circumference of the skirt the meeting loose ends of the cord are conveniently passed through a slit or buttonhole G, formed through 75 the material of the body below the stitched margin of the tuck and above the upper mar- gin of the insertion D and tied in a loose knot (indicated at H) on the under side of the skirt.

I am aware that detachable flounces and 80 ruffles for ladies' skirts, broadly considered, are old; but so far as I am aware these parts, where made removable, have been commonly applied by means of buttons, hooks and eyes, and devices of that general character. Such 85 devices are always objectionable in connection with the laundering of the article for the reason that they are exceedingly liable to get broken or torn off entirely, thus damaging the skirt itself, to say nothing of the necessity of 90 replacing the fastening devices themselves. The fastening means which I employ, in contradistinction to such devices, will pass through the laundry with no more liability to 95 injury than is possessed by the skirt or the flounce itself. With my device the flounce may be applied and removed with the utmost ease and simplicity, while the wearing qual- 100 ties of the parts comprising the uniting means, if properly made, are no less than the wearing qualities of the skirt itself.

It will be obvious that the employment of the tuck B is unnecessary to the carrying out of my invention; but I prefer to use it in con-

nnection therewith and as a feature thereof for the reason that it affords a protection to the joint between the ruffle and the skirt, besides concealing the existence of the joint and 5 causing the flounce to present the external appearance of an integral portion of the skirt itself. It will also be obvious that my invention is also applicable to other articles of underwear to which ruffles or flounces are commonly adapted. Such applications of my improved fastening device I consider within the spirit and purview of my invention.

I claim—

1. As an improved article of manufacture, 15 a skirt comprising a skirt-body and a flounce or ruffle therefor, and means detachably securing the latter to the former comprising a strip of open-work beading secured around the skirt-body, a strip of open-work beading 20 secured around the upper margin of the flounce, and a cord laced through said beading-strips and locking them together, substantially as described.
2. As an improved article of manufacture, 25 a skirt comprising a skirt-body, a flounce or ruffle to be applied to the lower portion thereof, and means detachably uniting said flounce to the skirt-body comprising a strip of open-work beading stitched around the outside of 30 the skirt-body, a similar strip of beading stitched around the upper margin of the

flounce, and a cord lacing through said beading-strips locking them together, substantially as described.

3. As an improved article of manufacture, 35 a skirt comprising a skirt-body having a tuck formed therearound, and a flounce or ruffle therefor, a strip of open-work beading stitched to the skirt-body beneath said tuck, a similar strip of beading stitched to the upper margin 40 of the flounce, and a cord laced through said beading-strips and thus detachably securing the flounce to the skirt-body, substantially as described.

4. As an improved article of manufacture, 45 a skirt comprising a skirt-body having a tuck formed therearound and a slit or buttonhole formed therethrough beneath the tuck, and a flounce or ruffle therefor, a strip of open-work beading stitched along its upper margin 50 to the skirt-body beneath the tuck thereof, a similar strip of beading stitched along its lower margin to the upper margin of the flounce, and an interlocking cord laced through said beading-strips and having its 55 meeting ends passed through said slit and tied therebehind, substantially as described.

GEORGE LEWIS.
